UNITED STATES PATENT OFFICE

2,542,902

WATER PUMP

Horace A. Chubbuck, Dearborn, Mich., assignor to
 Ford Motor Company, Dearborn, Mich., a corporation of Delaware

Application January 31, 1946, Serial No. 644,560

1 Claim. (Cl. 103—103)

1

This invention is directed to a liquid pump, and more particularly to a centrifugal water pump. This invention will be particularly described in connection with a coolant circulating pump on an internal combustion engine, but is by no means so limited and is capable of use in any application requiring a pump of similar characteristics.

An object of this invention is to provide a pump the discharge of which is free from pulsations and oscillations.

Another object of this invention is to provide a pump of high efficiency particularly at high speeds and when pumping water the temperature of which closely approximates the boiling point.

With these and other objects in view, the invention consists in the arrangement, combination and construction of the various parts of my improved device, as described in the accompanying specification, claimed in the claim and illustrated in the accompanying drawings, in which:

Figure 1 is a plan view with parts broken away of the pump housing.

Figure 2 is an elevation of the pump housing.

Figure 3 is a central longitudinal vertical section of a completed pump.

Figure 4 is a plan view of the pump impeller.

Figure 5 is a perspective view partially broken away of the pump housing.

Figure 6 is a section taken along the line 6—6 in Figure 4.

The overall efficiency of the single stage centrifugal pumps previously employed to circulate the coolant in internal combustion engines has been quite low. This inefficiency, per se, has not been a serious consideration since the total power requirements of the pumps are relatively small. The chief difficulty encountered in the operation of the usual coolant pumps has been a sharp decline in delivery at high speeds. Since it is at high speeds that a large volume of coolant is required, it is readily seen that a pump characterized by a drooping delivery curve at high speeds must be designed on a much larger scale than one without such a drooping curve.

The solution of this problem proposed by applicant is readily understandable from a consideration of the drawings and more particularly from simultaneous consideration of Figures 1, 2, 3 and 5. Turning first to Figure 3, there is shown a vertical section of the pump and the associated driving mechanism. The pump casing is generally indicated by 10. This casing is usually an iron casting and is provided with an impeller cavity 13, an inlet 14, an inlet cavity 15, a separator 16 and separator opening 17 leading into discharge

2

cavity 18. This casing is further provided with a heater connection 24 threaded to receive a hot water heater fitting, a seal opening 34 which accommodates a seal 27 and an opening 12 into 5 which is pressed ball bearing 26 which carries shaft 25. This shaft 25 carries on one end an impeller 21 and on the other end hub 31 and pulley 32 secured by retainer ring 33. The pump seal is generally indicated at 27 and is pressed 10 into seal opening 34. This seal comprises a metal seal casing 35 which is pressed into seal opening 34 and which carries elastomer seal bellows 29. Graphite sealing ring 30 is attached to elastomer seal bellows 29 and urged towards the left by coil 15 seal spring 28. This seal cooperates with face 37 of impeller hub 36 (Figures 4 and 6).

The general relations of the various parts of the pump are shown in Figure 3. However, in the interest of clarity, Figures 1, 2 and 5 show only

20 the pump housing, the seal and all moving parts having been omitted. An important distinction between this pump and those of the prior art is the provision of ramp 20 in inlet cavity 15. The structure of this ramp is best seen in Figure 5

25 although it is also shown in Figures 1 and 3. The flow of coolant through the pump is illustrated by the arrows in Figures 2, 3 and 5 as entering 30 through inlet 14 flowing into inlet cavity 15 past separator 16 and impeller 21 into discharge cavity 18.

35 Due to the rigid space and weight limitations inherent in automotive design, all dimensions of this pump must be kept as small as possible. This causes the impeller hub 36 diameter to be a substantial fraction of the diameter of inlet cavity 15 and separator opening 17. The impeller hub

40 rotation tends in previous designs to cause a corresponding rotation of the water in inlet cavity 15. This rotation in inlet cavity 15 is highly undesirable inasmuch as it causes inlet cavity 15 to act as the first stage of a two stage pump, the second stage being in impeller cavity 13. These 45 two stages are of course pumping in opposite directions and it is this opposition which results in a drop in efficiency at high speed. These opposing actions also give rise to an oscillating or pulsating delivery in which the variations in pressure amount to as much as five inches of mercury.

50 Applicant has effectively cured this defect and greatly enhanced the efficiency of this type of pump by the simple expedient depicted in Figures 1, 2 and 5. Ordinarily inlet cavity 15 is annular or doughnut shaped. Applicant has modified the configuration of inlet cavity 15 by inserting ramp 20 as shown most clearly in Figure 5

The exterior outline of ramp 20 is shown in Figure 2. This deflecting ramp covers about one hundred twenty degrees around the periphery of inlet cavity 15 and in this one hundred twenty degrees slopes from the rear to the front of inlet cavity 15. Any tendency of the water to rotate in inlet cavity 15 causes a flow along the slope of ramp 20 and directly into impeller cavity 13.

Figures 1, 2 and 5 show face 11 which is bolted tightly against a mating face on the engine block (not shown) by bolts placed in bolt holes 38. In Figure 1 is shown bypass 19 leading directly from inlet cavity 15 to the engine block. The object of this bypass is to prevent the development of hot spots in the engine during the warming-up period while normal circulation through the radiator is cut off by the engine thermostats. During normal operation circulation through bypass 19 is prevented by a valve action of the thermostats and all circulation is through the radiator.

Figures 4 and 6 depict in detail a preferred form of impeller. Figure 4 is a plan view showing full blades 22, half blades 23 and impeller hub face 37. Figure 6 is a sectional view taken along the line 6-6 of Figure 4. This figure shows full blades 22, impeller hub 36 and impeller hub face 37.

To test this pump so modified and compare it with standard pumps, a test set up was established in which the pumps to be tested were caused to pump hot water in a circuit containing a number 11 orifice having a diameter of eleven-sixteenths of an inch. Pumping 200° F. water, the maximum pressure drop across the orifice with the modified pump was found to be 17.8 pounds per square inch at 5425 R. P. M. A standard pump with the same impeller also working on 200° F. water reached a maximum pressure of 11.1 pounds per square inch at 4900 R. P. M., and

at 5425 R. P. M. the pressure was only 10.7 pounds per square inch. At 210° F., the modified pump generated 5.05 pounds per square inch at 3100 R. P. M. and the standard pump 3.6 pounds per square inch at 2600 R. P. M. and 2.9 pounds per square inch at 3100 R. P. M.

Some changes may be made in the arrangement, construction and combination of the various parts of my improved device, and it is intended to cover by the claim such changes as may be reasonably included within the scope thereof.

I claim as my invention:

A centrifugal coolant pump for internal combustion engines comprising an impeller chamber, 15 an intake cavity, a rotating member in the intake cavity whose diameter is a substantial fraction of the intake cavity diameter and which is exposed directly to the coolant therein, a ramp in the intake cavity, and a separator disposed between the 20 impeller chamber and the intake cavity, the direction of the slope of said ramp being such that coolant rotating with the shaft in the intake cavity will be given an axial component of motion towards the impeller chamber, the separator being 25 so arranged that no axial flow is possible from said ramp into the impeller chamber except by passing around the inner periphery of the separator.

HORACE A. CHUBBUCK.
